TOOL FOR RELEASING CLOCK SPRINGS

Beryl F. Cameron, Cambridge, Ohio

Application July 27, 1949, Serial No. 107,035

3 Claims. (Cl. 81—6)

1

This invention pertains to tools but more particularly and specifically to a jeweler's tool.

In the repair of clocks and the like one of the most difficult and laborious details is that of releasing, without injury to the other working parts of the clock and the worker's hands, the clock spring and the present invention has as its primary object provision of a tool by which the clock springs of any and all makes and types of clocks can be quickly and easily released without injury to the springs.

Another object of the invention is the provision of a device of the character described composed of a minimum number of parts all of which are extremely simple of construction thus providing a tool which is comparatively cheap of manufacture and assembly and therefore cheap of production.

Another and further object of the invention is the provision of a tool of the character described which is sturdy and simple and therefore highly durable.

Another object of the invention is the provision of a device of the character described which although simple of construction is highly efficient in operation.

Another and further object of the invention is the provision of a device of the character described which is both practical and convenient in use.

Other objects, advantages and novel features of construction of the invention will appear from the following description when read in the light of the accompanying drawings.

In the drawings:

Fig. 1 is a view in side elevation of the tool, a portion of the figure being broken away and shown in vertical section.

Fig. 2 is a view in side elevation of the tool, the figure being taken at right angles to Fig. 1.

Fig. 3 is a horizontal sectional view on the line 3—3 of Fig. 1, looking in the direction indicated by arrows.

Fig. 4 is a fragmentary vertical sectional view on the line 4—4 of Fig. 1, looking in the direction indicated by arrows.

The tool comprises a pair of opposed handle-like elements 1 and 2 pivotally connected to one another at 3 whereby upon manual manipulation the opposed jaws 4 and 5 of the handles may be moved toward and away from one another.

A short distance from their connected ends the handles are enlarged to provide circular plate-like elements 6 and 7 each of which centrally is cut out to provide through the handles a bore 8.

2

A shaft, designated as an entirety by A, comprises a round center portion 9 which is loosely rotatable in the bore 8 and has extending ends 10 and 11 at opposite sides of the handles. Each of the extending ends of the shaft is provided with a longitudinal bore, the two bores being 12 and 13. Each of the bores is provided with opposed cut-out portions to provide in the shaft end 10 a longitudinal slot 14 and in the shaft end 11 a longitudinal slot 15. The shaft extensions 10 and 11 can be formed integral with the center shaft portion 9 or as separate attachable and detachable parts should this be found to be desirable.

15 The center portion 9 of the shaft carries a washer-like element 16 which constitutes on the shaft a circumferential flange. This flange is disposed between the handle jaws 4 and 5 and carries some suitable material, such as brake lining or the like, 17 on its opposite faces. However should it be found more desirable this braking material could be formed on or secured to the jaws of the handles.

15 The extending ends 10 and 11 of the shaft are 25 for the purpose of engaging clock keys of different sizes. A clock key B is shown positioned in the shaft end 11. The wings 18 and 19 of the key handle are disposed in the shaft slot 15 which holds the key against axial rotation. The 30 key spindle 20 extends outwardly beyond the shaft end. The two sizes of shaft ends illustrated would ordinarily be sufficient to accommodate all sizes of clock keys, but as mentioned, these shaft ends could be made detachable so that 35 other shaft ends could be substituted were this necessary for proper operation in connection with any particular and unusual clock key.

In operation the key is inserted in the outwardly extending end of the winding arbor or shaft, as illustrated in Fig. 1, and the socket 21 of the key is fitted over the arbor of the clock spring. The tool handles 1 and 2 are gripped, in substantially the same manner that a pair of pinchers is gripped, and the pawl of the clock 45 is manually moved or lifted out of engagement with the ratchet wheel of the spring arbor. It will be evident that then by releasing the pressure upon the handles 1 and 2 the braking action on the shaft washer or flange 16 can be 50 eased off or tightened at will so as to permit the clock spring to unwind under complete control and without any danger of injury.

Departures from the specific construction illustrated in the drawings can be made without departure from the inventive concept and the in-

vention is to be limited only within the scope of the hereinafter following claims.

What I claim is:

1. A tool of the character described comprising, a shaft having means for quickly detachably engaging the spring arbor of a clock or the like, a pair of inter-connected jawed handles supporting said shaft for free axial rotation, the jaws being movable toward and away from one another in a direction longitudinal of the longitudinal axis of the shaft, the shaft intermediate the jaws being provided with an outwardly extending circumferential flange, and the opposite sides of said flange being engaged by the inner faces of the jaws upon movement of the jaws towards one another.

2. A tool of the character described comprising, a shaft having means for quickly detachably engaging the spring arbor of a clock or the like, a pair of inter-connected jawed handles supporting said shaft for free axial rotation, the jaws being movable toward and away from one another in a direction longitudinal of the longitudinal axis of the shaft, the shaft intermediate the jaws being provided with a portion the opposite faces of which are engaged by the inner faces of the jaws upon movement of the jaws toward one another, and the inner faces of the jaws carrying means for promoting and increas-

ing the frictional engagement between the jaws and said shaft portion.

3. A tool of the character described comprising, a shaft having means for quickly detachably engaging the spring arbor of a clock or the like, a pair of inter-connected jawed handles supporting said shaft for free axial rotation, the jaws being movable toward and away from one another in a direction longitudinal of the longitudinal axis of the shaft, the shaft intermediate the jaws of the handles being provided with an outwardly extending circumferential flange the opposite faces of which are engaged by the inner faces of the jaws upon movement of the jaws toward one another, and the inner faces of the jaws being provided with a friction material acting to promote and increase the frictional holding engagement between the jaws and the shaft flange.
